FRONT PANEL UNIT FOR A WALL OVEN OR THE LIKE

Walter R. Kimberley, Signal Mountain, Tenn., assignor to Samuel Stamping & Enameling Company, Chattanooga, Tenn., a corporation of Tennessee

Application March 27, 1958, Serial No. 50,201

Term of patent 14 years

(Cl. D81—25)

The figure is a perspective view of a front panel unit for a wall oven, showing my new design.

The dominant features of the design reside in the portions shown in full lines.

I claim:

The ornamental design for a front panel unit for a wall oven or the like, as shown and described.
